Patented Nov. 21, 1922.

UNITED STATES PATENT OFFICE.

GEORGE LEWIS HOGAN, OF CHICAGO, ILLINOIS, ASSIGNOR OF ONE-HALF TO A. H. MARSHALL, OF CHICAGO, ILLINOIS.

ATTACHMENT FOR ROLL-PAPER CUTTERS FOR PRINTING AND SEALING WRAPPERS.

Application filed January 30, 1920. Serial No. 355,226.

To all whom it may concern:

Be it known that I, GEORGE LEWIS HOGAN, a citizen of the United States, residing at Chicago, in the county of Cook and State 5 of Illinois, have invented a new and useful Attachment for Roll-Paper Cutters for Printing and Sealing Wrappers, of which the following is a specification.

My invention relates to improvements in 10 devices to attach to the ordinary roll paper cutter whereby the wrapping paper may be printed as it is pulled off the roll and sealed when wrapped around the package, and relates particularly to, first a construction that 15 will permit the printing roller a free motion to and from the paper roll without having to counteract the resistance due to inertia of the frame carrying the printing roller, second to provide a simple and quick 20 method of removing one printing roller and substituting another, third to afford a simple form of springs for feeding the printing roller to the roll paper as it is unwound and the roll becomes smaller, fourth to provide 25 a simple form of guard to protect the mechanism and render it easily accessible, and fifth to provide a simple means of sealing the package after wrapped.

I attain these objects by the mechanism 30 illustrated in the accompanying drawings in which—

Figure 1 is a side view of the entire mechanism mounted on an ordinary paper cutter; Figure 2 is an elevation of such 35 mechanism in which the side supports of the paper cutter are omitted; Figure 3 is a plan view of the mechanism with the gum tape holder removed; Figure 4 is a perspective view showing the notched bearings and slide covers for the axis of the printing roller; and Figure 5 is a part sectional view on plane 5 illustrating how the cover guard is hinged to the frame work of the machine.

Similar numerals refer to similar parts 40 throughout the several views.

The paper cutter F is of the ordinary type such as used in general trade, G is the roll of paper. The clamp member Y—Z—W 45 has two downward projecting jaws, a clamp screw 8 is fitted in the front jaw Y by which the upper cross member 20 may be clamped between this clamp screw and the back jaw Z. The clamp member terminates 50 in two ear extensions W in the rear to

which is hinged a U shaped frame Q to have a swinging movement about the hinge axes P in a direction to and from the paper roll G. J—K are two respective ink rollers working preferably in slotted bearings 60 R—S and pressed together by a torsion spring 18 and by which pressure the inking rollers are brought into working relation with the printing roller B which is mounted on an axis that extends outward 65 on each side of the U shaped frame support. N—N are bearings milled in from the top of the frame of a longitudinal shape being longer in a direction towards the paper roll, the axes E—E are made to work loosely 70 in these bearings and the frame is prevented from dropping away from such axes by slide members D—D which are bent over the edges of the frame Q and notched out in their central portion so that when the printing roller is placed in position its axes will be held in these notched bearings by sliding the members D—D to cover the top 75 opening of such bearings.

X—X are screw rods screwed into opposite sides of the main clamp member around which spiral springs T—T are wound one end of each respective spring resting against Z and its other end forming an arm that presses down upon the axes of the printing roller E—E thus giving it pressure to follow the inequalities of the paper roll by the freedom of the axes E—E from the frame Q allowing the printing roller to respond quickly without the counteracting 80 inertia of the frame which is used only as a support and to give rigidity for tracking. In order to get a number of turns on the spring T I form a recess or narrow the clamp member at the part where the screw 85 rods X—X are located.

I provide a cover guard to protect the mechanism which is comprised preferably of a piece of sheet metal bent down at the upper end and around screws O—O which project 100 through the frame Q, the sheet of metal is then bent to cover and conform with the position of the rollers and bent over at its other end to snap over the lower end of the frame Q.

The printing roller B is preferably of wood around which type formed of rubber composition may be tacked.

To the main clamp member Y—Z—W I attach an upward extending bar 13 through 110

which is fixed a screw axis 4 fitted with a bar washer 2 and clamp nut 3 for holding a roll of gum tape in position to allow it to rotate in unwinding about the axis 4. I also 5 attach to this main clamp member another upward extending bar curved outward from the face of the roll of tape and terminating in a knife edge for cutting the tape as it is pulled out over its curved surface under a 10 guide band 5. I also attach a moistener preferably a cup and sponge under this curved member 6 for moistening the tape after it is cut off, such cup is indicated by 7 and such sponge by 12.

15 The operation of the device is as follows. The cover C is raised and ink applied to the rollers L-K, the cover is then put down and the machine clamped on to the upper bar 20 of the paper cutter. The spring arms T-T 20 will press the printing roller against the roll of wrapping paper which when pulled off will by friction cause the printing roller to revolve and print the outer layer of paper, which is then torn off and wrapped around 25 the package and the operator then takes hold of the end of the gum tape 1 and pulls off as long a piece as desired and gives it a downward jerk over the knife edge 6 and thus cuts it off and then passes it over the wet sponge 30 moistening the gum and applies it to seal the wrapper.

I claim:

1. The combination with a paper-roll

holder, of a printing attachment comprising a support, a printing roller, a frame having spaced side members carrying the printing roller, said frame being pivoted to the aforesaid support to swing in a direction to bring the printing roller into contact with the paper roll, means for loosely supporting the printing roller in the frame to permit movement toward and from the paper roll independent of the frame, and spring for maintaining the printing contact of the printing roller with the paper roll, said springs being anchored to the aforesaid support and bearing against the journals of the printing roller.

2. The combination with a paper-roll holder, of a printing attachment comprising a support, a printing roller having end journals, a frame having spaced side members between which the roller is located and provided with bearing apertures in which the journals of the roller seat, said apertures being elongated in the direction of the paper-roll and the printing roller journals being slidable therein, a support to which the frame is pivoted to permit the printing roller to swing toward and from the paper-roll, and springs anchored to the aforesaid support and bearing against the roller journals for maintaining a yielding contact of the printing roller with the paper roll.

GEORGE LEWIS HOGAN.
